United States Patent [19]
Chambers

[11] Des. 261,809
[45]  Nov. 10, 1981

[54] ASPHALT PLANT CONTROL HOUSE

[76] Inventor: Richard F. Chambers, 8431 Dayton
Pike, Daisy, Tenn. 37319

[] Term: 14 Years

[21] Appl. No.: 145,995

[22] Filed: May 2, 1980

[51] Int. Cl. .... D25—03

[52] U.S. Cl. D25/22; D12/103;
D25/33

[58] Field of Search D25/1, 3, 4, 11, 16,
D25/17, 18, 22, 23, 24, 25, 32, 33, 59; D12/101,
103; 425/88; 52/23, 24

[56]

References Cited

U.S. PATENT DOCUMENTS

D. 232,719 9/1974 Mize et al. D25/32
D. 250,840 1/1979 Chambers D25/22

Primary Examiner—A. Hugo Word
Attorney, Agent, or Firm—Lamont Johnston

[57]

CLAIM

The ornamental design for an asphalt plant control house, substantially as shown and described.

DESCRIPTION

FIG. 1 is a perspective view from the front, left side and above showing my new design; and
FIG. 2 is a perspective view from the rear, right side and above.

The bottom not shown is conventionally plain and unornamented.

U.S. Patent

Nov. 10, 1981

Des. 261,809

FIG. 1

FIG. 2